Attorney.

UNITED STATES PATENT OFFICE.

SILAS M. FORD, OF ST. PAUL, MINNESOTA.

LATH-BOARD.

1,236,283.

Specification of Letters Patent.

Patented Aug. 7, 1917.

Application filed August 21, 1916. Serial No. 116,145.

To all whom it may concern:

Be it known that I, SILAS M. FORD, a citizen of the United States, residing at St. Paul, in the county of Ramsey and State 5 of Minnesota, have invented certain new and useful Improvements in Lath-Boards, of which the following is a specification.

One object of my invention is to provide 10 in a lath-board, simplified means for stiffening said lath-board longitudinally.

Another object of my invention is to provide 15 in a lath-board, simplified means for stiffening said lath-board longitudinally by placing stiffening means in a series of slots 15 cut in the corrugations of the board, and furthermore provide means for sealing the slots after the stiffening means has been placed therein.

Another object of my invention is to provide 20 in a lath-board stiffened by the longitudinal means placed in slots cut in the corrugations of the board, means for preventing the stiffening means from slipping from position.

Another object of my invention is to provide 25 in a corrugated lath-board, means for creating additional air space under said lath-board when placed on a wall.

With these and incidental objects in view 30 the invention consists of certain novel features of construction and combination of parts, the essential elements of which are hereinafter described with reference to the drawing which accompanies and forms a 35 part of this specification.

In the drawing Figure 1 is an isometric view of the preferred construction of my invention, and Fig. 2 is a similar view of a modification thereof.

40 In Fig. 1, the sheet 1 of water-proof material has a strand 2 laid into the slots 3 formed in the dove-tailed shaped faces on one side of the sheet to a depth substantially equal to that of the width of the flat wire.

45 When the wire has been so positioned, a strip or ribbon 4 of suitable cloth or material is cemented or glued over the slot and strand, thereby preventing any longitudinal displacement of the corrugations, the movement 50 of the strand itself, and also serving as a seal for the slot in which the strand has been laid.

This ribbon may be of considerable thickness and serves to space the faces of the 55 sheet from the wall on which the board is

used, and thereby maintains an air space behind the entire sheet, in addition to the air spaces 5 formed by the shape of the corrugated sheet.

In the modification shown in Fig. 2 the 60 sheet is corrugated in the ordinary style instead of in the dove-tailed formation shown in Fig. 1, and a strand 6 is laid in a similar slot, as heretofore described, and the ribbon 7 serves the same purpose as the ribbon 65 4 shown in Fig. 1.

The strand 8 is shown laid parallel with the plane of the corrugated sheet instead of transversely, as strands 2 and 6 are shown, and it is evident that a strand may 70 be placed in either position within the scope of this invention, and also that round wires or fibrous cords may be used instead of the flat strands.

While I have described my invention and 75 illustrated it in several particular designs, I do not wish it understood that I limit myself to these constructions as the application of my invention may be varied in many ways within the scope of the following 80 claims.

Claims:

1. In a lath-board, the combination of a sheet of suitable material formed into corrugations, a series of slots extending transversely across the face of each of said corrugations, reinforcing means positioned in said series of slots, and a ribbon cemented over said reinforcing means for maintaining the relative position of said corrugations and said stiffening means. 85

2. In a lath-board, the combination of a sheet of suitable material formed into a corrugated shape, a series of transverse slots across the face of said corrugations, a stiffening means extending longitudinally of said sheet and positioned in said series of slots, and means associated therewith for sealing said slots over said stiffening means. 95

3. In a lath-board, the combination of a sheet of suitable material corrugated into a dove-tailed shaped formation having alternate lath-like faces and depressions on either side thereof, webs connecting the series of faces on each side, a series of slots through the lath-like faces on one side, and extending downwardly into the webs on that side, and stiffening means extending longitudinally of said sheet and positioned in said series of slots. 105

4. In a lath-board, the combination of a sheet of suitable material corrugated into a dove-tailed shaped formation having alternate lath-like faces and depressions on either side thereof, webs connecting the series of faces on each side, a series of slots through the lath-like faces on one side and

extending downwardly into the webs on that side, stiffening means extending longitudinally of said sheet and positioned in said series of slots and a ribbon cemented to said series of faces over said stiffening means, thereby sealing said series of slots.

SILAS M. FORD.
